[57] CLAIM

The ornamental design for a stand for a hair dryer and curling iron, as shown and described.

DESCRIPTION

FIG. 1 is a perspective view of a stand for hair dryer and curling iron showing our new design;

FIG. 2 is a top plan view thereof;

FIG. 3 is a left side elevational view thereof;

FIG. 4 is a front elevational view thereof;

FIG. 5 is a rear elevational view thereof.

The right side elevational view is a mirror image of FIG. 3 and the bottom plan view is plain.
